VACUUM SWITCH

William K. Rankin and Claude D. Hayward,
Lansdowne, Pa., assignors to General Electric
Company, a corporation of New York

Application February 23, 1934, Serial No. 712,522

5 Claims. (Cl. 200—144)

Our invention relates to vacuum switches, more particularly to vacuum switches wherein a magnetic field is utilized to effect rapid interruption of a high tension power circuit.

5 The use of a coiled conductor for producing a magnetic field is accompanied by mechanical problems involving compression and bursting stresses where large currents necessarily traverse the coil. These stresses may be of such magnitude that mechanical failure of the coils results unless special provision is made for strengthening the coil structure. A vacuum switch having such coil structure for producing a magnetic field must be so constructed that the entire arrangement is simple and readily prepared for high vacuum operation, as by well known degassing methods wherein the switch parts are heated to drive off occluded gases.

20 The object of the present invention is the provision of an improved vacuum switch of the aforesaid type which shall be simple, mechanically strong and compact in construction, and reliable and efficient in operation.

25 Our invention will be more fully set forth in the following description referring to the accompanying drawing, and the features of novelty which characterize our invention will be pointed out with particularity in the claims annexed to and forming a part of this specification.

30 Referring to the drawing, Fig. 1 is an elevational view, partly in section, of a high tension vacuum switch embodying the present invention; Fig. 2 is an enlarged sectional view of the switch contact and coil structure illustrated in Fig. 1, and Fig. 3 is a plan view of the upper contact shown in Fig. 2.

35 The vacuum switch shown in Fig. 1 comprises an evacuated casing 1 in which are disposed relatively movable contacts 2 and 3, the contact 2 being stationary and connected to a lead-in conductor stud 4 and the contact 3 being mounted at the end of a pivoted operating rod 5 which is sealed, as by a flexible metallic diaphragm 6, to a lateral extension 1' of the switch casing. Operation of the switch is effected by suitable actuating means connected to the operating rod 5 exteriorly of the switch casing for moving the contact 3 into and out of engagement with the stationary contact 2. The operating rod 5 is of conducting material so as to constitute one terminal of the switch, the other terminal comprising the extension 4' of the lead-in conductor stud 4.

40 The conductor stud 4 is mounted and insulated with respect to the casing 1 by means of insulat-

5 ing cylinders 7 and 8 interposed between the upper wall of the casing and flanges 9 and 10 at opposite ends of the conductor stud, respectively. The sealing means for the conductor stud comprises an insulating sleeve 11 flexibly connected and sealed to the casing 1 and to a flange 12 welded to the conductor stud by flexible metallic diaphragms 13 and 14, respectively. A cone-like shield 15 is connected to the lower end of the conductor stud for preventing formation of a short-circuiting deposition of metal particles on the insulator 7. The switch structure above described is mounted on a high voltage insulator 16.

45 For the purpose of providing a radial magnetic field for effecting rapid interruption of high tension power circuits upon separation of contacts 2 and 3, as described with more particularity and claimed in an application Serial No. 712,521 for Vacuum switches, filed concurrently herewith by W. K. Rankin, a coiled conductor 17 connected in series with the circuit to be interrupted is disposed between the conductor stud 4 and the stationary contact 2.

50 Referring more particularly to Fig. 2, the coiled conductor 17, which is in the form of a substantially flat strip helically disposed, is electrically connected through its upper turn to the flange 9 which is in turn suitably connected as by screw-threaded engagement to the conductor stud 4 and 55 through its lower turn to the stationary contact 2. As illustrated, the contact 2 comprises a circular or disk-like conducting member having a flared annular flange 2' and a central opening at 18. As illustrated by Fig. 3, which is a plan view 35 looking upwards of the contact 2, the contact is slotted as at 19 for the purpose of preventing circulation of currents and for minimizing heating due to the magnetic field of the coil 17 and the flange 9 is similarly slotted at 20. It will be 40 apparent that the contact 2 may be slotted at a plurality of points around the periphery thereof if desired.

45 The assembly of the coil with respect to the contact structure includes a conducting disk 21 which is secured with respect to the upper flange 9 as by bolts 22 which extend through the coiled conductor 17 and are insulated therefrom by an insulating sleeve 23 composed of glass or ceramic material which may be degassed without difficulty. 50 The structure above described would be adequate in case of moderate currents traversing the coiled conductor 17 but would in all probability fail in the case of heavy short circuits.

55 For the purpose of providing for heavy com-

pression and bursting stresses imposed on the coil 17 adjacent turns of the coil at uniform intervals have recesses as hemispherical indentations at 17' so as to receive balls 24 or the like composed of a strong insulating material, a ceramic material such as a glass having a low coefficient of expansion known to the trade as "Pyrex" being a suitable example. In general, the insulating material used in the switch must be of such a nature that it will withstand temperatures between 300° and 700° C. in vacuum without deterioration.

As illustrated in Fig. 3, the insulating balls 24 and supporting bolts 22 are disposed around the coil 17 in any suitable manner, depending of course on the mechanical requirements of the structure. The balls 24 which are capable of withstanding high compression and shearing stresses not only serve to insulate the turns of the coil with respect to each other and to prevent short circuiting of the same due to high compression stresses but also to prevent bursting of the coil. In fact, increase of the strength of the magnetic field serves to wedge the balls 24 into such high pressure engagement with the adjacent turns of the coil that the structure is self-locking and more firmly braced during heavy currents. It will be apparent that the insulating bracing members between the turns of the coil 17 may 30 assume the form of cylinders, wedges, or the like.

The bursting force acting on the coil 17 can be considered as acting in the same way as a spiral spring which has been wound tight by torsion applied at its ends. The spring becomes smaller 35 in diameter when wound up but increases in diameter when released. Winding up the spring and soldering the turns together at a number of points parallel with its axis would prevent unwinding but such an arrangement is obviously 40 out of the question in a coil wherein each turn is to be electrically insulated with respect to adjacent turns.

The insulating balls above described likewise serve as keys to prevent rotation of the turns of the coil upon each other. In order that the coil turns may rotate with respect to each other, the insulating balls must either shear, enlarge the ball pockets by side thrusts or roll out of the pockets by spreading of the turns. The coil is 45 preferably proportioned so that the force tending to compress the coil is large relative to the force per turn tending to enlarge the coil diameter and since these forces increase substantially as the square of the current there will always be sufficient force to maintain the balls tightly seated 50 in their pockets.

A central insulating cylinder 25 composed of a suitable ceramic material or the like is positioned between the upper and lower flanges 9 and 21, respectively, of the coil structure and shares part of the compressive force acting on coil 17. The flange 21 connected to the lower part of the coil is electrically connected and secured as by a welded joint 26 to the inner face 60 of the contact 2 which is composed of a suitable conducting material as copper.

The movable contact 3 which likewise comprises a conducting disk-like member composed of copper and flared as at 3' similarly to contact 2 is 65 provided with a securing flange 27 at its inner surface to which is connected a stud 5' secured to the operating rod 6. The contact 3, however, is not slotted and comprises a continuous conducting path extending around the periphery of the contact. Accordingly, when the contacts 2 and 3

are separated the magnetic field produced by the coil 17 induces eddy currents in the contact 3 which in turn set up a countermagnetic field opposing the main field of the coil 17 as illustrated by the directional lines F of the fields. The resulting magnetic field between the contacts 2 and 3 is radial with respect to the contact surfaces so that the stream of ions and the cathode spot which are formed upon initial separation of high tension circuit terminals in a high vacuum 10 are moved and rotated as presently described at very high speed around the peripheries of the contacts.

In order to prevent localizing of the ion stream and cathode spot at the center of the contacts 15 where the magnetic field is the weakest, the co-acting contact faces of the contacts 2 and 3 are cut away or dished as at 28 and 29, respectively, so that the actual contact separation occurs near the outer peripheries of the contacts. The recess 20 28 in the contact 2 has a diameter slightly greater than the mean diameter of the coil turns so that current flowing from the lower turn of the coil through the contact to the cathode spot must be in a radially outward direction. The action 25 of the field resulting from this current is such that the ion stream is moved towards the rim of the contact. The ion stream and cathode spot are, therefore, positively moved toward the contact peripheries and rapidly rotated at the outer 30 flared edges of the contacts with the result that the circuit is quickly interrupted.

It should be understood that our invention is not limited to specific details of construction and arrangement thereof herein illustrated, and 35 that changes and modifications may occur to one skilled in the art without departing from the spirit of our invention.

What we claim as new and desire to secure by Letters Patent of the United States, is:

1. In a vacuum switch comprising an evacuated casing and relatively movable contacts disposed therein, a coiled substantially flat conductor connected in series with said contacts for producing a magnetic field adjacent the coacting contact 40 surfaces thereof, and insulating locking members individually disposed between adjacent turns of said coiled conductor, each member positioned in recesses formed in opposing faces of adjacent turns for resisting compression and bursting forces acting on said coil.

2. In a vacuum switch comprising an evacuated casing and relatively movable contacts disposed therein, a coiled conductor connected in series with said contacts for producing a magnetic field 55 adjacent the coacting contact surfaces thereof, the adjacent turns of said conductor having substantially flat opposing faces, and means for bracing said coiled conductor with respect to compression and bursting forces including a plurality 60 of insulating balls disposed between said turns and positioned by pockets formed in said conductor.

3. In a vacuum switch comprising an evacuated casing, relatively movable contact structure 65 disposed therein comprising a disk-like contact, a coil connected in series with the circuit to be interrupted mounted within the said casing and secured with respect to said stationary contact, and a coacting disk-like contact forming a continuous circular conducting path related to said coil so that eddy currents for producing an opposing field are generated in said coacting contact, said contacts having peripheries flared in 70 75

opposite directions and arranged to break the circuit adjacent said peripheries.

4. In a vacuum switch comprising an evacuated casing, relatively movable contact structure disposed therein comprising a stationary disk-like contact flared at its periphery, a coil connected to said contact for producing a magnetic field, and a coaxial disk-like contact forming a continuous circular conducting path and likewise flared at its periphery movable with respect to said stationary contact and related to said coil so that eddy currents for producing an opposing field are generated in said movable contact, said opposing fields producing a radial field between 10 said contacts, said contacts provided with circular recesses at the central portions thereof so that the contact separation takes place near the pe-

ripheries of said contacts and the electron stream is rapidly rotated by said radial field towards the outer flared peripheries of said contacts.

5. A coil structure for producing a magnetic field comprising a substantially flat helical conductor the turns of which are closely spaced, and insulating members composed of a strong ceramic material or the like individually disposed between adjacent turns of said coil and positioned in recesses in said conductor, said insulating members 10 separately locked in position by compression stresses acting on said coil so as to maintain the turns of said coil spaced and insulated with respect to each other.
